[57] CLAIM

The ornamental design for a handle for vegetation-cutting tool, as shown in the drawings.

DESCRIPTION

- FIG. 1 is a right-hand side perspective view of a preferred embodiment of a handle for a vegetation-cutting tool in accordance with the present invention;
- FIG. 2 is a bottom view of the handle of FIG. 1;
- FIG. 3 is a top view of the handle of FIG. 1;
- FIG. 4 is a rear view of the handle of FIG. 1;
- FIG. 5 is a front view of the handle shown in FIG. 1;
- FIG. 6 is a right side view of the handle shown in FIG. 1;
- FIG. 7 is a left side view of the handle of FIG. 1;
- FIG. 8 is a perspective view of the right-hand side of a handle for a vegetation-cutting tool in accordance with an alternative preferred embodiment of the present invention;
- FIG. 9 is a bottom view of the handle of FIG. 8;
- FIG. 10 is a top view of the handle of FIG. 8;
- FIG. 11 is a rear view of the handle of FIG. 8;
- FIG. 12 is a front view of the handle of FIG. 8;
- FIG. 13 is a right side view of the handle of FIG. 8; and,
- FIG. 14 is a left side view of the handle of FIG. 8.
